DESIGN FOR A FINGER RING OR SIMILAR ARTICLE

Herman B. Sacks, New York, and Philip Krasnow, Brooklyn, N. Y.

Application June 28, 1935, Serial No. 57,450

Term of patent 3½ years

To all whom it may concern:

Be it known that we, Herman B. Sacks, residing at the Borough of Manhattan, city, county, and State of New York, and Philip Krasnow, residing at the Borough of Brooklyn, county of Kings, city and State of New York, both citizens of the United States of America, have invented a new, original, and ornamental Design for a Finger Ring or Similar Article, of which the following is a specification, reference being had to the accompanying drawing, forming part thereof, in which, Figure 1 is a perspective view of a finger ring showing our new design, and Fig. 2 is a sectional view thereof on line 2—2, of Fig. 1. The jewels shown in Figs. 1 and 2 are continued along the entire periphery of the ring.

We claim:

The ornamental design for a finger ring or similar article as shown and described.

Signed at New York city, this 26th day of June 1935.

HERMAN B. SACKS.
PHILIP KRASNOW.
